RACE COURSE GAME

Henrietta Ehret, St. Louis, Mo.

Application July 22, 1936, Serial No. 92,138

3 Claims. (Cl. 273—86)

This invention relates to games of the race course variety, wherein any one of a plurality of objects or puppets may arrive at, or be in closer proximity to, a stationary goal or finishing line, in advance of the remainder at the end of the game.

In general terms therefor, this device comprises a plurality of circular tracks or discs, adapted to be rotated about a stationary center post. The tracks are connected by spokes or braces, to collars which are caused to revolve around ballbearing assemblies mounted on the center post.

Obviously the operative apparatus for a game of this nature must so function that it is impossible for the participants to predict in advance which one of the racing puppets will be the winner.

Also, it is necessary to line up the racing objects in proper formation before the start of the race, and thereafter to maintain them in such formation until each player selects the particular racing object which in his opinion will win the race.

Further it is desirable that any one of the players may at a given signal, by a simple operation, cause the apparatus to start and finish the race.

The principal object of my invention therefore, is to provide a simple, inexpensive yet efficient device whereby the various ends may be attained.

Features of the invention are the simplicity of the novel mechanism employed to line up the racing objects, to maintain them in racing formation until the start of the race, and the mechanism whereby any one may set the game in motion.

Other objects and features not specifically mentioned above, will be apparent or pointed out in the following description, and in the drawings forming part of this application.

In the drawings, which illustrate my invention as applied to a horse race game,

Fig. 1 is a plan view of the device;

Fig. 2 is a similar view, taken at a level beneath the horses, tracks, etc. to better illustrate the mechanism therebelow;

Fig. 3 is a vertical section taken approximately on the line 3—3 of Fig. 1;

Fig. 4 is a similar view taken approximately on the line 4—4 of Fig. 2;

Fig. 5 is a view similar to Fig. 2, illustrating the position assumed by the various components of the device prior to the start of a race;

Fig. 6 is an elevation of the tripping member

and its associated parts, as viewed from the lower right hand portion of Fig. 5, looking toward the center post.

At numeral 1 is shown a wooden base, upon which is mounted as by screws, a rectangular metal plate 2.

Threaded into a hole 3, or otherwise secured to the plate 2, is a vertical cylindrical post 4, carrying near its lower extremity a bushing 5, which is in turn surrounded by the inner raceway member of a single row ballbearing assembly 5a of common design. A collar 6, is press fitted to the outer raceway member of said ballbearing, is integral with a laterally extending arm 7. A roller 8, adapted to ride upon the upper surface of base 1, is mounted on said arm, which also carries an upwardly extending handle 9, for purposes to be described.

Likewise fixed to collar 6, is a second arm 10, secured to a more or less arcuate member 11, whose inner extremity is also fixed to said collar. Fastened to the member 11, is a trip member 12, and a laterally extending arm 13, for reasons to be explained.

An integral arm 14, extends upwardly from arm 7, which also carries a suitable support or bracket for roller 8.

Referring more particularly to Fig. 3. A plurality of collars 18, with spacing members 19, therebetween, and above the uppermost of them, encompass and are each securely attached to the outer raceway member of a double row ballbearing assembly mounted on center post 4. Set screws 20, hold spacing collars 19, in place. Spokes or braces 21, welded to collars 18, extend angularly and upwardly therefrom, being fixed to the underside of circular tracks 22. Each track 22, is a concentric ring of increasing diameter, clearance between their peripheries being provided as shown.

Numerals 23, indicate for illustrative purposes only, (since dogs, automobiles, motorcycles etc. may be substituted), horses with jockeys thereon.

Obviously each horse or other object fixed to each track carries a mark or numeral distinguishing it from the other entrants.

Secured as by screw 25, to the upper extremity of center post 4, is a disc 24, whose outer periphery is slightly less than the inner periphery of the innermost track. A plate or board 26, having a circular recess slightly larger than the outer periphery of the outermost track 22, is fastened in any suitable manner to any appropriate support or cabinet (not shown). The goal or fin-

ishing line is of course indicated either on plate 26, or disc 24, or both.

A member 27, hereinafter called the starter, is in the form of an inverted U, and has formed on 5 the lower extremity of its legs, an integral perforated wing portion as shown in Fig. 3, adapted to slide upon starter track 29, the latter being a more or less C-shaped rod as shown in Fig. 2. A 10 guide rail or guard 28, fixed to base 1, generally follows the contour of track 29, but converges gradually nearer to the center post for a purpose to be explained.

A heavy coil spring 30, surrounding track 29, is fixed at one end to a standard 31, whose out- 15 standing base flange 32, is screwed to base 1. Starter track 29, is likewise screwed at one end to said standard 31, and to a similar standard at its other end. At its other end coil spring 30 is attached to starter 27.

20 An arm 33, has a pivoted connection at 41, to a ring 34, screwed to base plate.

A helical spring 35, is mounted in the bore of a tubular member 36, rotatably supported in ring 34. The lower end of spring 35, is fixed to base 1, 25 the upper end being fastened to and bearing against an arm 37, tending to force said arm toward the center post. Arm 37, is integral with tubular member 36, and carries an upwardly extending aligning finger 38, as well as a substantially V-shaped member 39, these parts serving to align the racing objects.

A spring 40, secured at one end to any suitable portion of base 1, and at its other end to an up- 35 standing extension 42, of arm 33, tends to pull said arm in a clockwise direction (Fig. 2), about pivot 41. A notch 36a formed in the outer periphery of member 36, however, acts as a stop, engaging the edge of extension 42, thus limiting the clockwise travel of arm 33.

40 A trigger 43, pivotally mounted as at 44, on a bracket 46, fixed to track 29, has an integral exten- 45 sion 45, to which is attached a coil spring 49, as illustrated, said spring being fastened also to stationary guard 28. Spring 49, tends to pull extension 45, in a clockwise direction, against a 50 limiting stop 48a or shoulder formed on a laterally extending member 48, also fixed to guide rail 28. An auxiliary, arcuate, stationary guide mem- 55 ber for starter 27, is shown it 50.

50 The function of the various elements above referred to will now be explained. Assuming that a race has been run, and the device is at rest, the various parts occupy the position illustrated in Fig. 2. Spring 30, is slack, starter 27, finds its self in its extreme right position, and arm 7 with 55 its handle 9, is held slightly ahead of the starter which bears against it. Trigger 43 is held in position to subsequently engage starter 27, by spring 49, which pulls it in clockwise direction toward a stop on member 48, and trips member 12, having the triple duty of tripping the trigger, retarding the inward movement of the aligning assembly for a necessary interval, and of striking arm 33 to release extension 42 from notch in tubular 60 member 36, bears against extension 45. Its exact position obviously is dependent upon the position of lever 7.

65 As illustrated, at this time arm 13 bears against 70 arm 37 and finger 38, outwardly from the center of the device, and against the influence of spring 35, which would force said elements inwardly toward the center post. Lever 33, its extension 42, seated in said notch of tubular member 36, 75 stabilizes the aligning assembly by virtue of spring

40. It is to be understood of course, that the tension of spring 35, is such as to overcome the influence of spring 40, so that in this initial set-up, member 39, bears against arm 13, in a counter-clockwise direction. Also obviously, the exact position of arm 33, is dependent upon the position of arm 7, which would be approximately in the Fig. 2 position.

Assuming further that a new race is now to take place, an operator grasps handle 9, and pulls it clockwise. By virtue of arm 14, engaging starter 27, said starter is forced to ride clockwise on track 29, until its leading wing is engaged by the hook on trigger 43, which will be in position to engage it, and hold it firmly until released.

During the movement of starter 27, toward trigger 43, guard rail 28, continually tends to force bight of said starter inwardly toward the center post, the tendency of spring 30, being to force it against said rail. Guard rail 50, is so designed as to retard such inward movement of the starter for such a length of time as is necessary for the aligning mechanism to function, thereby obviating any interference between starter 27, and braces 21, at the time of aligning finger 38, 20 comes into play as will be explained.

Leftward movement of arm 7, and therefore starter 27, obviously revolves elements 6, 10, 11, 12, and 13, about center post 4, in a clockwise direction, permitting spring 49, to contract and 30 pull extension 45, inwardly against said shoulder stop on member 48. During part of this movement, arm 13, restrains the inward movement of the aligning assembly 36, 37, 38, 39. Continued leftward movement of lever 7, causes 35 the rounded portion of trip 12, to perform this duty. At the same time that starter 27 is engaged by catch trigger 43, however, member 12, severs engagement with element 39, and contacts arm 33, releasing extension 42, from its confining 40 notch and allowing aligning assembly 37, 38, 39, to swing inwardly under energy of spring 35. This is so because spring 35, is stronger than spring 40, and is so wound as to bring aligner 38, 45 in toward center, when its inward movement is arrested as will appear.

Each track has a plurality of the braces 21. In the embodiment illustrated and described herein, four such braces support each track. The racing objects 23, on each track, are fixed, 50 one each directly above the supporting flanges on said braces. Obviously therefore, each track carries four puppets, and has four braces, ninety degrees apart. The duty of the finger 38, is to align the puppets in sets of three evenly about 55 the course, since those on the inner track occupy positions different than those on the intermediate and outer tracks and vice versa, due to the finish of the preceding race. In its inward movement therefore, finger 38, strikes three of said braces 60 and carries them in a clockwise direction until the directly opposite three braces contact and are stopped by the starter 27, which has previously become engaged and is held fast by trigger 43. The travel of the starter, from its right to its 65 left or caught position, follows the curvature of track 29, until it snaps into the catch 43, spring 49, being thereby extended and consequently holding said starter securely against the obvious tendency of now distended spring 30, to pull it 70 to the right. As noted above guard rail 28, gradually and gently brings the bight of starter 27, closer into the center until at the point where it is clutched by member 43, the starter is practically in a vertical position so that three of the 75

braces 21, are engaged by its right leg, as said braces are made to bear against it by finger 38, as described. The latter action naturally does not take place until after the starter is clutched.

5 The bight of the U-shaped starter is so shaped in order to obviate any interference with the braces 21, in its gradual inward movement to starting position under the influence of guard rail 28.

10 It is now apparent that under this arrangement, the twelve racing objects are lined up for the start of the race, in four sets of three each, ninety degrees apart. The operator may now move arm 7, to the right, until member 12, is 15 approximate to extension 45, or he may allow it to remain in the position it assumed when starter was clutched.

10 For explanatory purpose, the former is assumed. Consequently, member 12, upon disengaging arm 33, permits extension 42, to again seat itself in its notch by virtue of spring 40, and pivot 41. Member 12, thereafter, riding along the inner leg of V-shaped member 39, begins to move the aligning finger 38, outwardly away 25 from the now motionless braces 21, which outward movement is completed by arm 13, as the cycle continues. The arrangement of parts at this time is obviously identical with the Fig. 2 illustration with this exception: the starter 21, 30 is clutched at 43, and spring 30, is extended to almost the length of track 29.

When the players have chosen their respective racers, handle 9, is flipped to the right, members 12 and 11, trip clutch 43, starter 21, with great 35 force moves suddenly to the right under the compression of spring 30. The tracks begin to whirl at great speed about their ball-bearing centers, simulating an actual race, with the racers passing and repassing one another until 40 finally all the tracks come to rest with one or the other of the contenders at or nearest the goal.

Obviously as starter 21, travels with spring 30, to the right, it moves outwardly along guard 28, to clear the succeeding set of braces after having 45 imparted great momentum to the tracks.

The uncertainty of the winner, due to the springs, ball-bearing mountings of the tracks, the impact of the starter etc., is considered an important feature of my invention. The device is 50 of simple design and may be easily manufactured. The particular details of construction illustrated, obviously admit of considerable modification, and I do not wish to be restricted to the precise embodiment shown in the drawings.

55 Having thus described my invention, I claim:

1. A race course game, comprising a base, a center post mounted thereon, ball bearing assemblies mounted on said center post in spaced vertical relation, braces fixed to collars mounted on 60 said bearing assemblies, circular tracks fixed to said braces, racing objects in spaced relation mounted on said tracks, a starter member slidably mounted on an arcuate horizontal track, a heavy coil spring secured to said starter at one end and to the base at its other end, a horizontal lever rotatably mounted on said center post for clockwise movement of a diametrically opposed struc-

ture, said movement causing an aligning finger to move inwardly to align the racing objects on predetermined spaced radial lines emanating from the center post, a vertical extension on said horizontal lever to advance said starter, and a 5 clutch mechanism for maintaining said starter in a stationary position until its release is desired.

2. A race course game, comprising a base, a center post mounted thereon, ball bearing assemblies mounted on said center post in spaced vertical relation, braces fixed to collars mounted on said bearing assemblies, circular tracks fixed to said braces, racing objects in spaced relation mounted on said tracks, means for aligning said objects in precise starting formation, said means 10 comprising a vertical aligning finger mounted on a spring actuated inwardly moving structure, pivotally mounted on said base, means for maintaining said objects in such aligned position, comprising a starter, an arcuate horizontal track on 15 which said starter is slidably mounted, a spring fixed at its ends to the starter and the base and surrounding said track, guide rails insuring proper positioning of said starter, a clutch mechanism mounted on said base, and a horizontal 20 lever rotatably mounted about said center post, an integral upwardly extending arm for engagement with said starter, so that clockwise movement of the lever, causes clockwise travel of the 25 starter and expansion of said spring, until said 30 clutch mechanism engages said starter, whereby the starter in conjunction with said aligning finger, stabilizes and maintains said racing objects in starting formation until released.

3. A race course game, comprising a base, a center post mounted thereon, ball bearing assemblies mounted on said center post in spaced vertical relation, braces fixed to collars mounted on said bearing assemblies, circular tracks supported by and fixed to said braces, said braces 40 having racing objects in spaced relation mounted thereon, an operating lever rotatably mounted on the center post, a spring actuated aligning structure for positioning said objects in precise starting formation, said structure including a vertical 45 aligning finger, whose inward and outward movement is controlled by said operating lever, a starter and a clutch mechanism adapted to maintain said objects in such aligned position, a heavy coil spring fixed at one end to the base and at the 50 other to the starter, an upwardly extending arm integral with said operating lever for forcing said starter into engagement with the clutching mechanism, thereby distending said spring, and means for releasing said starter and spring to impart a 55 whirling motion to the tracks, said means comprising a tripping member fixed to a radially opposite arm integral with the operating lever, so that counterclockwise movement of said lever effects first the withdrawal of the aligning finger, 60 and then the release of the starter, causing the tracks to whirl rapidly about the ball bearing assemblies by reason of the impact imparted to the braces by the starter due to the rapid compression of said spring.

HENRIETTA EHRET.
